UNITED STATES PATENT OFFICE

172,776

COMBINED BOOKCASE AND TABLE OR THE LIKE

Charles A. Baylon, Aberdeen, Wash.

Application December 14, 1953, Serial No. 28,037

Term of patent 14 years

(Cl. D33—2)

To all whom it may concern:

Be it known that I, Charles A. Baylon, have invented a new, original, and ornamental Design for Combined Bookcase and Table or the like, of which the following is a specification, reference being had to the accompanying drawing, forming a part hereof.

Figure 1 is a perspective view of a combined bookcase and table or the like, showing my new design; and

I claim:

The ornamental design for a combined bookcase and table or the like, as shown.
